CLAIM

The ornamental design for an ear piece, as shown and described.

DESCRIPTION

FIG. 1 is a front perspective view of an ear piece showing our new design.

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines in the Figures show portions of the ear piece which form no part of the claimed design.
